ALARM SIGNAL BOX HOUSING

Marilyn Calderoni, Springfield, and Edward P. Cheslock, Kennett Square, Pa., assignors to E. W. Bliss Company, Canton, Ohio, a corporation of Delaware

Filed May 29, 1968, Ser. No. 12,122

Term of patent 14 years

Int. Cl. D29—01

U.S. Cl. D72—1

FIG. 2

FIG. 1

FIG. 3

FIG. 4

FIG. 5

FIGURE 1 is a perspective view of an alarm signal box housing showing our design;

FIGURE 2 is a front elevational view thereof;

FIGURE 3 is a bottom perspective view looking toward the top of FIGURE 2;

FIGURE 4 is a top perspective view looking toward the bottom of FIGURE 2; and,

FIGURE 5 is the front elevational view of FIGURE 2, with the hinged cover panel pivoted upwardly.

The rear of the alarm signal box housing is plain in appearance.

The dominant features of our design reside in the portions shown in full lines.

We claim:

The ornamental design for an alarm signal box housing, substantially as shown and described.
